UNITED STATES PATENT OFFICE.

WILLIAM T. HICKS, OF BLOOMINGTON, INDIANA.

FENCE-POST.

1,244,607.

Specification of Letters Patent.

Patented Oct. 30, 1917.

Application filed January 18, 1913. Serial No. 742,930.

To all whom it may concern:

Be it known that I, WILLIAM T. HICKS, a citizen of the United States, residing at Bloomington, Monroe county, and State of Indiana, have invented and discovered certain new and useful Improvements in Fence Posts, of which the following is a specification.

In the manufacture and use of wire supports for posts of the character forming the subject matter of my Patent No. 1,045,027, some difficulty may be encountered because the thickness of the fence wire being greater than the necessary thickness of the tie-plate will result in the knuckle, or bent portion of the wire, bearing against the surface of the post and preventing said plate from laying smoothly and snugly against the post, thus permitting foreign substances to accumulate between the plate and the post and also causing the knuckle, or crimp, in the wire to wear into the surface of the post and through the glazed or outer portion thereof, so as to admit moisture to the interior or coarser structure of the core, with harmful results.

My said invention consists, therefore, in an improvement in the post whereby these objections are overcome, all as will be hereinafter more fully described and claimed.

Referring to the accompanying drawings, which are made a part hereof and on which similar reference characters indicate similar parts:

Figure 1 is a side elevation of a concrete fence post showing a series of fence wires supported thereon by my improved wire support, and the post itself embodying the improvement above referred to.

Fig. 2 a perspective view of one of the wire supports of the character used on this specially designed form of post and in conjunction with which the improvement is adapted to coöperate,

Fig. 3 a cross section through the post above one of the wire supports, as on the dotted line 3—3 in Fig. 1.

In said drawings the portions marked A represent the post; B the tie of the wire support; C the tie-plate thereof, and D the fence wires.

The post A is preferably formed of concrete, as indicated in Fig. 3, reinforced by a woven wire basket or form 10 embedded therein between a fine concrete mixture 11,

which forms the exterior surface of the post, and a coarse concrete mixture 12, which forms its core.

In the formation of said post the side against which the tie-plate C is adapted to rest is preferably formed flat, but the cross sectional form of the post is not material to my invention. Extending from top to bottom of said post, and formed when the same is molded, is a vertical shallow crescent shaped, or concave, groove a of a sufficient depth to accommodate the knuckle, or crimp, d in the fence wires D.

In use the wire supports are applied to the posts in the same manner as described in the above mentioned Letters Patent, the vertical groove a permitting them to be placed in any position in relation to each other throughout the height of the posts with the knuckles d in said groove a. The respective fence wires D are passed through a transverse slot 13 in a vertical corrugation c in the respective plates C and the pins 14 are inserted through said corrugations in front of said wires and through the crimp therein. The tongues 15 are bent down to impinge against the bent over ends of the ties B in the same manner as in the said above mentioned patent.

By means of this improvement the tie-plate C may be made of light thin metal, the inter-engaging connection aiding in the supporting qualities and making a heavy plate unnecessary. The groove also permits the plate to rest closely against the surface of the post and cover the juncture of the fence wires with said plate and the post completely. A structure is thus secured that is not only smooth and neat but one that will form a joint well protected from the weather and secure in its attachments. In the construction, when found necessary, or desirable, a small quantity of green concrete, may be placed above the edge of the tie plates, or immediately above the heads of the pins 14 in the groove a, to prevent the supports from slipping upward on the post, as when the post is positioned in a hollow and the fence wires extend upwardly each way therefrom causing an upward strain on said supports. The heads of pins 14 will, ordinarily, substantially conform to the contour of the groove a and thus prevent foreign substances from getting into said groove behind the tie-plates.

Having thus fully described my said invention what I claim as new and desire to secure by Letters Patent, is—

The combination of a fence post formed with a smooth imperforate surface having a vertical groove in one side, extending continuously from top to bottom, an adjustable wire support adapted to encircle said post and rest against one side thereof with a recess to receive the crimp of the wire and a vertical socket to receive a pin, a pin mounted in said socket and adapted to extend in front of the crimp in the wire, and the wire mounted with its crimp registering with the

recess in said wire support and the vertical groove in the post, whereby the wire may be supported in or adjusted to any position desired on said post and be out of wearing contact with its surface, substantially as set forth.

In witness whereof, I have hereunto set my hand and seal at Indianapolis, Indiana, this 28th day of December, A. D. nineteen hundred and twelve.

WILLIAM T. HICKS. [L.S.]
